ABSTRACT: A generally triangular shaped game board having three sets of lines disposed on the surface thereof with each set of lines radiating from different apices of an equilateral triangle and intersecting the other sets of lines at a plurality of points over the surface of the game board. Holes are provided at the intersection of the lines and a peg is provided for being positioned in any of the plurality of holes. Three strings are respectively connected between the peg and the three vertices of the triangle so that movement of a peg from one hole to another causes the three areas defined by the strings and the sides of the triangle to be changed simultaneously each time the peg is moved to a new location.

GAME IN WHICH MOVEMENT OF PEG CAUSES BOARD AREAS TO CHANGE

BACKGROUND OF THE INVENTION

The present invention relates generally to entertainment apparatus of the parlor game type and, more particularly, to a novel game and game board apparatus upon which the game is to be played.

Heretofore, most parlor games have involved the capture of an opponent's players such as in checkers or chess or the acquisition of title to property such as in "Monopoly." But few games, if any, have actually involved the direct and physical takeover of "property," that is, the surface area of the game board; and to my knowledge no prior art games have involved a balance of power concept wherein the acquisition of the property of one opponent may simultaneously add to the property of another opponent, and wherein the choice of moves to be made involves a consideration of the "relative strength" of both opponents.

OBJECTS OF THE INVENTION

It is therefore a primary object of the present invention to provide a novel game and associated apparatus wherein each of a plurality of players is initially assigned equal areas of the surface of a game board and each player plays independently against each of the other two opponents in an attempt to obtain control of the surface area of the game board initially possessed by his opponents.

Another object of the present invention is to provide a novel game board apparatus having means for constantly delineating the territories belonging to each player as they change throughout the course of the contest.

Still another object of the present invention is to provide a novel game board apparatus having a plurality of apertures placed in predetermined positions over the surface thereof and having lines drawn between certain ones of said apertures so as to indicate the possible moves which may be made by a moving player.

SUMMARY OF THE PRESENT INVENTION

In a preferred embodiment, the present invention includes a generally triangular-shaped game board having three sets of lines disposed on the surface thereof with each set of lines radiating from different apices of an equilateral triangle and intersecting the other sets of lines at a plurality of points over the surface of the game board. Holes are provided at the intersection of the lines and a peg is provided for being positioned in any of the plurality of holes. Three strings are respectively connected between the peg and the three points of the triangle so that movement of a peg from one hole to another causes the three areas defined by the strings and the sides of the triangle to be changed each time the peg is moved to a new location.

The apparatus also includes a plurality of plugs called "agents" which are assigned to each player and which may be positioned in certain ones of the apertures of the player's property. Also included are a unique set of eight-sided dice which are rolled in turn by each player and a set of rules which dictate the types of moves which may be made by the players in response to a roll of the dice.

IN THE DRAWING

FIG. 1 is a plan view showing the principal structural features of the upper surface of a game board in accordance with the present invention.

FIG. 2 is a bottom view of the game board illustrated in FIG. 1.

FIG. 3 is a diagram illustrating the manner in which the apertures and game lines of the game board are developed.

FIG. 4 is a detailed diagram of the game pattern provided on the upper surface of a game board in accordance with the present invention.

FIGS. 5 and 6 are respectively side and cross-sectional views of the die which is used in accordance with the present invention.

FIG. 7 is an illustration of a plug means in accordance with the present invention.

DETAILED DESCRIPTION OF A PREFERRED EMBODIMENT

The apparatus of the present invention is to be utilized in a fast-moving novel game of chance and strategy played by three persons in the preferred embodiment. At the onset of the game, each player is assigned a territory exactly equal to one-third of the area of an equilateral triangle and his objective is to enlarge his territory to such an extent that at least one of the territories of his opponents disappears. This is accomplished by his skill in manipulating certain plugs in a plurality of holes disposed in predetermined locations over the game board and by his luck in rolling two unconventional and unique dice which have a particular set of numbers appearing on the faces. Upon the rolling of the two dice, a number may be obtained therefrom which allows the player to move a peg from hole to hole according to the mathematical principle of random walk to determine the extend of the player's territory at any given stage of the game. The territory is determined by strings connected from the corners of the triangle to the peg.

Certain rules are provided which dictate the manner in which the plugs and peg are to be positioned upon the face of the board in response to a given roll of the dice. Since each player in the game is playing against the other two players, he is not only concerned with defeating an opponent, but must also maintain such assemblage of a balance of power so as to prevent the other opponent from winning the game by capitalizing on his moves.

Referring now to FIGS. 1 and 2 of the drawing, the overall structural features of a preferred embodiment of the present invention are illustrated. In this embodiment, the game board 10 is comprised of a generally triangular shaped planar surface 40 the points of which have been trimmed as indicated to reduce the overall size of the board. Disposed in the middle of the game board 10 is a triangularly shaped playing area 12 having a plurality of intersecting lines 14 and peg holes 16 the disposition of which will be more fully described with relation to FIGS. 3 and 4 of the drawing.

Three holes 18, 20 and 22 are provided at each of the apices of the triangular playing area 12 through which lengths of cord 24, 26 and 28 are respectively passed and their ends fastened to a peg 30. The other ends of the cords 24, 26 and 28 are attached to a rubber band 32 by means of three ring hooks 56 on the bottom side of the board 10 as illustrated in FIG. 2 of the drawing so as to enable the peg 30 to be positioned at any point over the surface of the area 12. The strings are thus kept taut so as to define straight lines between the peg 30 and the holes 18, 20 and 22 no matter where the peg is positioned over the playing area. Alternatively, the remote ends of the cords 24, 26 and 28 could be attached to any suitable contractible-expansive mechanism underneath the board which provides sufficient cord reserves to enable the peg 30 to move freely over the playing area on top.

Since the game involves a series of alternative moves in accordance with a predetermined set of rules, tables of movements may be provided on the three sides of the game board 10 at the positions 34, 36 and 38 as illustrated for the convenience of each player. These rules involve not only the movement of the peg 30, but also the placement of "agents" which are comprised of plugs such as are illustrated in FIG. 7 of the drawing which are variously positioned in the holes of the game board at the option of the players in response to the throwing of the dice. The particular rules included in the table are set forth in the table of movements set out below.

Turning now to FIGS. 3 and 4 of the drawing, the layout of the triangularly shaped game area will be disclosed in detail. As shown in FIG. 3, the playing area is constructed by starting

with an equilateral triangle 40 having apices coincident with openings 18, 20 and 22 and then drawing three fanned arrays of lines 42 from each apex to the opposite side of the triangle. In accordance with the preferred embodiment, a family of 13 straight lines 42 are drawn radiating from each of the points 18, 20 and 22 spaced apart at approximately 7° intervals about the respective apices. The points at which lines from all three sets of lines cross, holes are drilled for accommodating the peg 30 as well as the "agent" plugs which will be positioned in some of the holes in accordance with the rules of the game.

In FIG. 4, the complete playing area is depicted, and it will be noted that this area includes a plurality of small triangles of varying shapes and sizes defined by the lines radiating from the three apices such that a number of such small triangles will be included in the triangular subareas formed by the lengths of cord 24, 26 and 28 shown in FIG. 1, and the sides 19, 21 and 23 of the large triangle. It will be noted that since all of the lines radiate from the points 18, 20 and 22 a whole number or none of the small triangles will appear in each of the triangular subareas no matter which hole the peg 30 is positioned in. It will also be noted that the outer band of trapezoidal figures 42 defined by the two outer rows of holes are not divided into triangles for reasons which are to be explained below.

The game board pattern is divided into several zones which are variously colored so as to provide differentiation therebetween. The outermost band 44 might, for example, be colored purple while the band 46 might be colored red and the band 48 colored yellow. The innermost area 50 is colored green in the preferred embodiment. The zones defined by the colored areas determine into which of the various holes the plugs may be positioned as will be more fully described below.

Referring now to FIGS. 5 and 6 of the drawing, one of the octahedral dice used in playing the game is illustrated. The die 50 is made from a length of material having a regular octagonal cross section with its ends rounded off. On each of the eight faces of each die the numerals 0 through 7 are imprinted so that upon being thrown, one of the eight numbered faces will appear in the top position when the die comes to rest. For ease of identification, the numerals shown on the faces of the die may be provided in differing colors or, as an alternative, the numbers may be done away with and merely different colors may be provided. However, since the choice of game moves is determined by the numerical summation of the numbers or other indicia obtained by rolling the two dice, the type indicia used must correspond to the indicia utilized in the table of moves. Alternatively, any other suitable random number determining means could be used in place of the octahedral dice.

The "agents" used for purpose of plugging up some of the holes on the board during the process of playing the game are illustrated in FIG. 7. These agents 52 are merely flat-headed plugs which are of a suitable shape and size to be easily placed in the holes and removed therefrom by the players. The game typically consists of 27 agents of which three are colored yellow for use in the yellow zone, nine are colored green for use in the green zone, and 15 are colored red for use in the red zone. Although the agents may be made of any type of material, it has been found preferable to construct them out of iron so that they may be easily manipulated by a small magnet which may be provided to each of the players.

Turning now to the game itself and the method in which it is to be played, it should be pointed out that there are two types of movements which may be made in response to a single roll of the dice. The first is to move the peg 30 from one hole to another and the other is to move an agent from one hole to another. The movement of the peg 30 may be further characterized as moving from one hole to an adjacent hole connected by a straight line or as jumping over one or more agents obstructing its path so defined by the straight lines on the board. As a general rule, a player must make the move indicated by the rolling of the octadice whenever it is possible to do so. Otherwise, no movement is made. The moves and the alternative moves which may be made in response to the vari-

ous rolls of the octahedral dice are defined in the following table of movements.

TABLE OF MOVEMENTS

5	DICE ROLL	MOVES
10	(0)	Advance four holes
	(1)	Jump over two consecutive agents in one hop or shift three agents
	(2)	Retreat one hole
	(3)	Advance one hole
	(4)	or jump over one agent at most twice
	(5)	Advance two holes
	(6)	or jump over two consecutive agents in one hop
	(7)	Advance three holes
	(8)	or jump over three agents in two or three hops
	(9)	or jump over two consecutive agents in one hop
	(10)	Shift three agents
	(11)	Advance two holes
	(12)	or jump over one agent at most twice
	(13)	Advance one hole
	(14)	or shift three agents
		Advance two holes
		or shift three agents
		Jump over one agent at most twice
		or shift three agents
		Advance three holes
		Retreat one hole
		Jump over three agents in two or three hops
		or jump over two consecutive agents in one hop
		or shift two agents
		Make a free move

35 The choice of which of the instructions appearing in the table of movements are to be followed is determined by the sum of the numbers appearing on the two dice when they are rolled.

40 As mentioned above, a player's territory at any given time is defined by the subarea of the triangular playing area defined by the two strings and the side of the triangular playing area on his side of the board. The movement "advance one hole" means that the player is to move the peg to an adjacent vacant hole connected by straight lines in such a manner that the resultant number of holes in his new territory is not decreased. On the other hand, the movement "retreat one hole" means that the player is to move the peg to an adjacent hole connected by a straight line such that the resultant number of holes in his new territory has not increased, i.e., has decreased or remained the same.

55 45 50 55 The instruction "advance two holes" means that the movement "advance the hole" is effected twice and in each instance the resultant number of holes in the player's territory must not be decreased. Thus, this movement involves exactly two different vacant holes which need not lie along a straight line passing through the original location of the peg. Similarly, the movements "advance three holes" and "advance four holes" are made with exactly three and four different vacant holes respectively.

60 65 70 75 In a multi-hole advance movement, if there are obstructive agents causing one or more one-hole movements to be a retreat movement, no move is to be made. The instruction "jump over one agent at most twice" means that the player can jump over one agent or he can jump over two agents one at a time. In order for him to be able to jump over one agent, the peg must be positioned adjacent to the agent and the jumping must take place along the straight line connecting the peg and the agent to the immediate vacant hole beyond the agent. In order to jump twice over two different agents, the peg and the two agents to be jumped over must be so situated that the peg jumps over the

agents in two consecutive hops. However, the agents need not be in a straight line with the peg.

In order to comply with the "jump over two consecutive agents in one hop" instruction the only requirement is that the peg and the two agents must be in three consecutive holes on the same straight line so that the jumping takes place to the vacant hole immediately beyond the second agent. Any jumping movement must be performed as indicated if it is possible to do so, although it may be a retreating movement. To "jump over three agents in two or three hops," the peg and three different agents must be so situated that the peg may be jumped over the agents in two or three (but not one) consecutive hops. A single jump over three consecutive agents in a straight line, is not permitted in accordance with this move.

The "shift two agents" and "shift three agents" movement mean that the indicated number of agents anywhere on the board, with the exception of those under the string at that given moment, are to be transferred from the holes in which they appear to any other vacant holes on the board in the same color zone, except to those vacant holes under the string. Differently colored agents may be shifted under these movements. The movement "shift two agents" may be interpreted as to mean the interchange of two agents in the same color zone. Thus, amounting to no move at all. By the same interpretation, "shift three agents" may, in effect, be a shift of one agent.

In the table of movements, there are nine composite alternative movements indicated by the word "or." An alternative movement may be satisfied by effecting any one (but only one) of the alternatives at the player's option. If it is possible to carry out only one of the alternatives, then that alternative must be made even though it is not advantageous to the player. If it is impossible to effect any one of the stated alternatives, no move may be made.

The instruction "make a free move" means that any one (and only one) of the movements described above may be made at the player's option.

In playing the game, the peg 30 is initially set at the center hole of the board. Each one of the three players then takes nine agents, one yellow, three green and five red, and distributes them at will in the corresponding color zones of his own territory. No agents are to be placed in the holes under the string or in the holes in the purple zone. All 27 agents remain in their respective zones of the board throughout the play. The players then roll the octahedral dice to determine the order in which their turns are to be taken and once the order is determined, each player makes two moves. The first move is accomplished by rolling the two octahedral dice and obtaining a number which identifies the movement to be made according to the table of movements. Whenever it is possible to do so this indicated movement must be made even though it is against the interest of the player. The same player then rolls octahedral dice again to make a second move, completing his turn.

The objective of each player is to place the peg in a purple hole as far from his side of the board as possible according to his skill in manipulating legal movements so that his territory contains the maximum number of holes. The game ends whenever the peg is placed in any of the purple holes. The player to whom this purple hole belongs is the loser and receives no points. The other two players decide who the winner is according to their scores as determined below. The scores are determined by counting the number of nonpurple holes which are contained within the resulting subareas after one of the players has been overpowered. For convenience, these numbers are printed on either side of the boundary holes. These numbers represent all but the holes lying directly under the string in each of the subareas. The purple holes or boundary holes are used for the sole purpose of ending the game and keeping score and are not counted as holes to be gained.

The score of each player at the end of the game is deter-

mined by subtracting the number of agents within his territory from the number associated with the purple hole at which the game is ended. The player with a high score wins the game. This method of keeping score indicates that the number of agents used in a player's territory to win the game is counted against him. If a player succeeds in putting the peg 30 in the most distant purple hole from his side, he is the sole winner of 100 points (127 holes-27 agents) and both of his opponents receive no points. When several games are played, scores from each game are accumulated at the end to indicate the final winner.

Since each player is allowed to make two moves in each turn, a player acting on the offensive should use his first move to set up the agent to give himself a chance to jump over them 15 in the second move. Once territory is gained, he should avoid losing it by shifting the agents to block the return path of the peg, if possible, even at the sacrifice of a one- or two-hole advance movement. Usually three consecutive agents in a line are used for this purpose since the peg may not jump over such an arrangement. As the final point in the offense, a player should generally advance into the territory of the player who follows him in turn.

Defensive moves are an important aspect of this game also. Without adequate defense a more experienced player could 20 win the game with two or three turns. At the beginning of the game, a player should distribute his agents in such a manner that his opponents cannot readily jump over them. To have an effective defense in the process of playing the game, a player should not only shift the agents to discourage an opponent 25 from reaching a purple hole in his own territory, but also place the peg in an unfavorable position to prevent the next player from winning the game even to the point of aiding his other opponent at the expense of making retreating moves. Sometimes this may be done by placing the peg in a hole that is not 30 adjacent to any agent so that jumping is impossible. In the process of playing the game, a player should attempt to set up 35 a defense with a minimum number of agents in his own territory so as to obtain a higher score if he wins. For this reason, a player should keep in mind the number of potential agents in 40 his territory as he plays. These are the finer points of the game in which proficiency may be gained with a little experience.

Although the present invention has been described with reference to a preferred embodiment for accommodating three players, it is to be understood that the invention could 45 likewise be adapted to accommodate any number of players by modifying the game board layout. Moreover, after having read the above disclosure, it is contemplated that many alterations and modifications of the invention will become apparent to those skilled in the art. It is therefore to be understood that this description of a preferred embodiment is for 50 purposes of illustration only and is in no manner intended to be limiting. Accordingly, I intend that the appended claims be interpreted as covering all modifications which fall within the true spirit and scope of my invention.

55 What is claimed is:

1. Apparatus for playing a game of skill and chance comprising:
a game board having a playing surface;
a plurality of openings provided in said playing surface;
60 peg means for insertion into one of the openings at a time;
defining means for variably defining at least three areas on
said playing surface, one area being possessed by each
player;
said defining means including, extensible, continuous barrier
means extending from at least three points equally
spaced around the periphery of said playing surface and
intersecting at and connected to said peg means; and
said peg means and said barrier means cooperating in such a
manner as to enable every movement of said peg means
65 into one of said openings to redefine the areas of said
playing surface possessed by each player.
